UNITED STATES PATENT OFFICE.

JOHN PEARCE AND ERNEST DE LA CHAPELLE, OF OTTAWA, ILLINOIS.

GLASS-FURNACE.

SPECIFICATION forming part of Letters Patent No. 390,394, dated October 2, 1888.

Application filed April 6, 1888. Serial No. 269,808. (No model.)

To all whom it may concern:

Be it known that we, JOHN PEARCE and ERNEST DE LA CHAPELLE, both of Ottawa, in the county of La Salle and State of Illinois, 5 have invented certain new and useful Improvements in Glass-Furnaces; and we do hereby declare that the following is a full, clear, and exact description thereof, reference being had to the accompanying drawings, and to the letters of reference marked thereon, which form a part of this specification.

This invention relates to improvements in the construction of glass-furnaces for their better adaptation to the use of liquid fuel.

15 The invention consists in the matters hereinafter set forth, and pointed out in the appended claims.

In the accompanying drawings, Figure 1 is a central vertical section of a glass-furnace 20 containing our improvements, and Fig. 2 is a horizontal section through the line 22 of Fig. 1.

A represents the bed of the furnace, upon which rests the melting-pots B, and A' is the circular wall surrounding the melting chamber A².

25 C is the crown, and D is the conical chimney of the furnace.

E is the fire-box, and E' is the central space or upflue, through which the flames rise from 30 the fire-box E into the melting-chamber over the bed, whence the products of combustion pass outwardly through passages a in the circular wall A', surrounding the bed A, and thence into the chimney D.

35 E² represents an oil-burner, of any suitable construction, arranged in the fire-box to send its flames forward into the upflue E' and melting-chamber A², and G is an exterior canopy or hood projecting from the sides of the furnace over the pot-holes.

40 Duets for air are provided having their inlets above the opening a', through which the melting-pots are reached, and said ducts lead to the combustion-chamber E, so that they 45 convey the hot air from outside the furnace to said combustion-chamber, where it may be mixed with the gases and vapor furnished by the burner and add its oxygen in a heated condition to the flames. In the best form of 50 our invention of which we are now informed it is embodied in the devices shown in the

drawings, which consist in a central flue, F, leading from the space above the crown C downward through the melting-chamber and through the center of the upflue E' to the bottom thereof, where it connects with branches F', formed in any suitable manner in the masonry of the furnace, and leading from the lower end of the flue F to the opposite sides of the fire-box E, as indicated clearly in the drawings. Desirably these flues F' are curved, so as to direct their contents forwardly into the furnace fire-box in the direction taken by the combustible materials furnished by the burner, and also desirably the outlets or mouths of 60 said flues F' are arranged about opposite, or a little at the rear of opposite, the delivery end of the burner, as also shown. To convey outer air to the central flue, F, and also to obtain the benefit of the heat imparted to the outer 65 air from the mouths of the melting-pots, we provide the canopy G, located above the pot-holes a', which canopy may be single and continuous, as shown, or, in other words, extending around the entire furnace; also over the 70 crown of the furnace and at a little distance therefrom is located a sheet, G', giving a space, g, between the canopy and the sheet, and this space is connected with the space beneath the canopy G by any number of suitable 75 passages, g', through the wall of the chimney-base. By the use of this canopy the air which is heated by contact with the wall A' of the furnace, and particularly the air which is heated at the pot-holes a', is conducted 80 through the openings g' into the space g, and thence passes downward through the central flue, F, and branch flues F' into the fire-box 85 E. By this construction the air as it is fed into the fire-box is intensely heated, having 90 not only the benefit of the heat conveyed through the crown and wall of the flue F', but also that which it derives from the exterior 95 of the furnace and the heat escaping from the furnace at the pot-holes.

It is well-known that heated air fed to a fire produces a better combustion than cold air, and we therefore make no broad claim for the use of hot air to supply oxygen to a fire; but

We claim as our invention—

1. The combination, with a glass-furnace and a device for burning oil or other fluid

combustible in the fire-box thereof, of a projecting canopy over a pot-hole, and an air passage or passages arranged to take from the exterior of the furnace below the canopy air

5 which is heated at the pot-holes and to conduct the same into the fire-box.

2. The combination, with a glass-furnace, of a central air-flue, F, leading from above the crown, a passage or passages leading from the 10 exterior of the furnace to the top of said flue, and a passage or passages leading from the lower part of said flue into the fire box.

3. The combination, with a glass-furnace, of a canopy located over the pot-holes, and an 15 air flue or flues leading from beneath the canopy through the melting-chamber into the fire-box.

4. The combination, with a glass-furnace, of a central air-flue, F, leading from above the 20 crown and provided with a branch or branches leading into the fire-box, a sheet, G', arranged

over the crown and providing an air-space, g, a canopy, G, exterior to the furnace above the pot-holes, and passages leading from beneath the canopy to the space g.

25

5. The combination, with a glass-furnace and its fire-box containing a fluid-burner, of a central flue, F, communicating at its upper end with the exterior of the furnace, and one or more branches leading from the lower end 30 of the flue F to the fire-box and having their delivery ends directed toward the rear of the fire-box.

30

In testimony that we claim the foregoing as our invention we affix our signatures in presence of two witnesses.
